UNITED STATES PATENT OFFICE.

MARY E. CHAPMAN, OF SPRINGFIELD, MASSACHUSETTS.

DESIGN FOR A PICTURE.

43,667.

Specification for Design.

Patented Mar. 4, 1913.

Application filed October 15, 1912. Serial No. 725,916. Term of patent 3½ years.

To all whom it may concern:

Be it known that I, MARY E. CHAPMAN, a citizen of the United States of America, residing at Springfield, in the county of Hampden and State of Massachusetts, have invented a new, original, and ornamental Design for Pictures, of which the following is a specification, reference being had to the accompanying drawings, forming a part thereof.

In the drawings—Figure 1 is a top edge view of the picture shown in the view below, and Fig. 2 is a plan or front face view of a picture, showing my new design.

I claim:

The ornamental design for a picture as shown.

MARY E. CHAPMAN.

Witnesses:

F. A. CUTTER,
A. C. FAIRBANKS.
